UNITED STATES PATENT OFFICE.

CHARLES C. WIENTGE, OF PROVIDENCE, RHODE ISLAND.

DESIGN FOR A HANDLE FOR SPOONS, &c.

SPECIFICATION forming part of Design No. 22,719, dated August 22, 1893.

Application filed July 28, 1893. Serial No. 481,778. Term of patent 7 years.

To all whom it may concern:

Be it known that I, CHARLES C. WIENTGE, of Providence, in the county of Providence and State of Rhode Island, have invented and produced a new and original Design for the Handles of Spoons, Forks, and Similar Articles, of which the following is a specification, reference being had to the accompanying drawings, forming part thereof.

Figure 1 represents an obverse view of a handle attached to the bowl of a spoon and illustrating one portion of my new design. Fig. 2 represents a reverse view of the same.

The leading features of my new design for the handles of spoons, forks, &c., consist in the spreading lower base of the handle, the narrow neck, above the base, gradually increasing in width toward the upper portion, and a circular portion surmounted by a crown forming the upper end,—surface ornamentation, on the obverse, of scrolls extending radially downward from a petal-like ornament on the base, outer beadings extending along the edges of the neck and its enlargements, inner beadings slightly foliated toward the upper ends also on the neck and the enlargement thereof, a convex plain surface within the inner beadings, a combination of scrolls forming a border for the circular enlargement, a shell-like ornament on the surface of the enlargement and a crown surmounting the circular enlargement. On the reverse the surface ornamentation consists of edge beadings on the lower portion of the neck each branching into two beadings toward the enlarged portion of the neck, concavities between the beadings and between the separated branches thereof, combinations of scrolls forming a border for the circular enlargement and a reverse view of a crown above the enlargement.

In the drawings 3 represents the handle of a spoon of which 4 represents the bowl. It may, however, represent the tine portion of a fork, or any other similar article for which a handle is necessary. The outline of the handle commencing at 5—5 curves abruptly inward to the contracted neck, then gradually outward

to 6—6, again slightly inward to the juncture with the circular enlargement 7 around 5° which it extends to meet the outline of the crown-like ornament 8.

On the base 9, of the handle, and extending partially on to the article to which the handle is secured, are represented the radial scrolls 10 which extend from the petal-like ornament 11. Along the neck and its enlargement extend the outer edge beads 12—12 and the inner foliated beadings 13—13 which are separated toward the upper portion, the 60 foliations of the beadings 13—13 overlapping the space between them. Within the beadings 13—13 and extending into the center of the enlargement 7 is the convex portion 14 on which, within the scrolled-border 15, is represented 65 the shell ornament 16, and above the enlargement 7 the surface of the crown-ornament 8 simulates a frame mounted on a rim, and convex panels extending from the frame. On the reverse the beadings 17—17 extend along 70 the edges of the base 9 and the neck of the handle, branching toward the upper portion. Between these branches are concavities 18—18 and between the beadings is the concavity 19 extending into the center of the enlargement 7. Around this enlargement is a combination scroll-border 20 and surmounting this the surface simulates a rear view of a crown within the outlines.

What I claim is—

80

1. In the design for the handle of a spoon, or similar article, the obverse as herein shown and described.
2. In the design for the handle of a spoon, or similar article, the reverse as herein shown 85 and described.
3. The design for handles of spoons, forks, and similar articles as herein shown and described.

In witness whereof I have hereunto set my 90 hand.

CHARLES C. WIENTGE.
